UNITED STATES PATENT OFFICE.

HENRY A. WILLIAMS, OF TAUNTON, MASSACHUSETTS, ASSIGNOR TO THE
H. A. WILLIAMS MANUFACTURING COMPANY, OF SAME PLACE.

MACHINE FOR REDUCING METAL RODS.

SPECIFICATION forming part of Letters Patent No. 388,938, dated September 4, 1888.

Application filed March 8, 1886. Serial No. 194,455. (No model.)

To all whom it may concern:

Be it known that I, HENRY A. WILLIAMS, of Taunton, in the county of Bristol and State of Massachusetts, have invented a new and useful 5 Machine for Reducing Metal Rods, of which the following is a specification, reference being had to the accompanying drawings, in which—

Figure 1 is a plan showing so much of a rolling-machine as is necessary to show my invention. Fig. 2 is an end view with some of the parts removed for greater clearness. Figs. 3 and 4 are side views. Fig. 5 is a modification. Fig. 6 is a section on line $x-x$ of Fig. 1.

My invention is a machine which in its simplest form consists of a pair of rolls revolving in the same direction, every cross-section of each roll being concentric with its axis of revolution, as will be clear from a description in detail of that form of my machine shown in 15 the drawings.

The frame of the machine (illustrated by Figs. 1, 2, 3, 4, and 6) is composed of a bed, F, upon which are secured the end brackets, 2, and the intermediate brackets, 1. These brackets support the boxes of the rolls—that is, the bed F and brackets 1, 2 are the frame of the machine, which is a double machine—that is, 25 has two pairs of rolls, each pair embodying my invention.

The rolls A' A² are mounted in boxes D' D², and these boxes are supported in any suitable way, too well known to require description. These rolls A' A² and the rolls A A³ are connected in the usual way (indicated in Fig. 1) 30 to any suitable source of power to compel the rolls to revolve each on its axis, but in the same direction as A', and A² in the same direction as A³. The rolls A A³ are mounted each in its boxes D, and these boxes are so 35 mounted in brackets 1 that the roll A can be gradually moved bodily (while it is revolving on its axis) toward the roll A', and the roll A³ toward the roll A². The means shown for thus 40 moving the roll A toward A' and the roll A³ toward roll A² is the shaft D³ (journalled in brackets 1,) and having upon it eccentrics, as 45 shown in Figs. 1 and 2, acting on bars d, laid in recesses in the said brackets between the journal-boxes in the roll and the said eccentrics, 50 so that when the shaft D³ is rotated by the hand-wheel the eccentrics act on the said bars

and push them against the journal-boxes, thus moving the rolls A and A³ nearer the rolls A' and A². The rolls A and A³ will be moved away from the rolls A' A², as shown, by inserting between the said rolls the metal rod to be reduced. The bearers b b⁵ extend up from the frame of the machine sufficiently high to support the rod of metal to be reduced. 55

With the pair of rolls A A', I prefer that one of the bearers, b, shall be near the middle of the length of the rolls, and the other bearer, b⁵, near the free end of the rolls, as shown in Figs. 1 and 4; but with other forms of rolls, such as A² A³, the bearers are best arranged as shown at b³ b⁴ of Figs. 1 and 3. 60

In operating with the rolls A A' the roll A is first moved away from A', as shown, by inserting the metal rod B to be reduced between the said rolls, the said rod being supported by the bearer b, and its outer end placed in the bore of guide or bearer b⁵, which brings the axis of the rod B substantially parallel with the axes of the rolls A A'. (See Figs. 1 and 3.) With the rod in this position, and while both 70 rolls A A' are revolving in the same direction, the hand-wheel D is turned to cause the eccentrics to act on the bars d and move the roll A gradually toward roll A' until the rod B is nipped with the desired pressure at the proper 75 points in its length between the parts a a' of rolls A A', and as the roll A gradually approaches the roll A' the rod B is reduced in diameter and drawn into the form shown at B in Fig. 1. 80

It will be seen that the rod B is rotated rapidly on its axis as soon as it is nipped between the rolls A and A', and that its diameter is gradually reduced by the gradual approach of roll A toward roll A'. Its feed lengthwise is 85 caused by setting the rolls A A' so that while their axes are in substantially parallel planes yet the axes are not exactly parallel with each other. This is best done as illustrated in Figs. 1, 4, and 6, from which it will be seen that 90 while the rolls A A' appear to be parallel in Fig. 1 yet one end of A' is slightly lower than one end of A. This causes the rod B to be moved endwise out through the tube which forms part of the bearer or guide b⁵ as that 95 rod is rotated on its axis. 100

The rod B is cylindrical when first operated

on by the rolls A A', and is tapered at one end by the first operation and at the other end by the second operation, being thereby reduced approximately to the shape desired. It is then 5 placed between the rolls A² A³ and laid upon the bearers b³ b⁴. The roll A³ is then moved toward roll A², (as before explained,) and as soon as the rod B is nipped between them it is rapidly revolved upon its axis and reduced 10 to the desired shape, at the same time being solidified, hardened, straightened, and rounded. The rod is of course heated to the proper heat when the metal of which it is composed is not adapted to be rolled cold.

15 In Fig. 5 I have shown a modified form of my machine, in which the rolls are cylindrical, but with their axes inclined, so that when a rod is fed toward the rolls A⁴ A⁵ through the guide or bearer b⁵ its end will be nipped 20 between the rolls A⁴ A⁵ and reduced to a taper.

My machine is adapted to rolling not only tapers and irregular forms, as above explained, but also to rolling cylindrical rods. Thus if the blank be inserted between the 25 rolls A A' and then the roll A be moved toward the roll A' the desired distance and then

be held in that relation with the roll A' the rod will be reduced to a cylinder whose diameter will be equal to the distance between the parts a a' of rolls A A' after the roll A is 30 set with relation to roll A'; or if the rolls A² A³ were cylindrical, with their axes parallel, a cylindrical blank placed between them would be nipped as the roll A³ was moved toward roll A² and would be reduced in diameter and elongated. 35

What I claim is—

1. In a machine, a pair of rolls rotating in the same direction, combined with a shaft and an eccentric or cam mounted thereon, and by 40 which to move one of the said rolls bodily toward the other while the machine is in operation, substantially as described.

2. In a machine, a pair of rolls rotating in the same direction, combined with an eccentric or cam and a bar interposed between the said eccentric or cam and one of the said rolls, substantially as described. 45

HENRY A. WILLIAMS.
